ELECTRIC WALL SWITCH

Victor R. Despard, Syracuse, N. Y., assignor to Pass & Seymour, Inc., Syracuse, N. Y., a corporation of New York

Application March 7, 1955, Serial No. 34,897

Term of patent 14 years

(Cl. D26—13)

Fig. 1 is a front elevational view of an electric wall switch, showing my new design;

Fig. 2 is a side elevational view thereof;

Fig. 3 is a top plan view thereof; and

Fig. 4 is a fragmentary perspective view thereof, to an enlarged scale, the portions in broken lines being omitted for convenience in illustration.

The dominant features of my design reside in the portions shown in full lines.

I claim:

The ornamental design for an electric wall switch, substantially as shown and described.
